UNITED STATES PATENT OFFICE.

FREDERICK J. H. HAZARD, OF TORONTO, CANADA.

BATH-TUB.

SPECIFICATION forming part of Letters Patent No. 512,701, dated January 16, 1894.

Application filed April 19, 1893. Serial No. 470,936. (No model.)

To all whom it may concern:

Be it known that I, FREDERICK JAMES HAWORTH HAZARD, of the city of Toronto, in the county of York and Province of Ontario, 5 Canada, have invented a certain new and useful Improvement in Bath-Tubs, of which the following is a specification.

The object of the invention is to construct a cheaply made and neat bath-tub capable 10 of heating the water contained by it, and it consists, essentially, of a bath-tub having a metal lining strengthened by a wooden casing packed closely to the metal lining and held 15 in position by fitting into recesses formed in a metal frame to which the metal lining is attached, a chamber being formed below the bottom of the bath-tub and heated by a gas 20 stove or other suitable heating device, the whole being constructed substantially as hereinafter more particularly explained.

Figure 1, is a perspective view of my improved bath-tub partially broken away to expose its construction. Fig. 2, is a longitudinal section through *a*—*b*, Fig. 1. Fig. 3, is a 25 cross-section through *c*—*d*, Fig. 2. Fig. 4, is a perspective detail of one of the metal frames.

At the end of the bath-tub I place a metal frame composed of the posts *d*, extending from the legs *b*. Between the posts *d*, I extend 30 a curved flange *a*, designed to support the bottom of the inner lining *B*, the opposite end of the lining being supported by a similar frame. This lining may be made of a single heavy sheet of metal or preferably 35 of a light sheet of copper resting upon a sheet of light steel. The posts *d*, are shaped to receive and hold in position the wooden side casing *C*, which is covered with metal lining *B*, as shown. On the outside of the posts *d*, I form 40 a flange *e*, which forms a support for the wooden casing *C*, formed at the ends of the bath-tub.

In order to support the bottom of the metal lining *B*, I provide the girders *D*, each girder 45 resting in a socket *f*, formed in a flange *a*, as indicated. As the flanges *a*, are carried by a frame located at each end of the straight portion of the bath-tub, the girders *D*, form a solid support for the bottom of the bath-tub.

50 In order to form a chamber below the bot-

tom *B*, I provide a curved flange *g*, below the curved flange *a*, to constitute a support for a casing *E*, which casing forms a chamber *F*. In order to heat this chamber, I provide a gas stove *G*, or some other suitable heater pref- 55 erably connected so that it may be readily removed and replaced as may be required.

The sides or ends of the casing *E*, are preferably perforated so as to admit the air necessary for the proper combustion. 60

On the top of each post *d*, I form a T-shaped flange *h*, on which a cap piece *H*, is securely fastened.

In order to protect the bottom of the bath-tub from the excessive heat of the stove, I prefer to reinforce it by an extra sheet of metal. 65

Should the bath-tub be made without a chamber *F*, I raise the flange *g*, closer to the flange *a*, just sufficient space being left to permit a casing of wood to be inserted around the bottom of the bath-tub similar to the casing *C*. This casing may be arranged between the girders *D*, or should it be found preferable to place the wooden casing in direct contact with the whole of the bottom, the sockets *f*, might be placed in the bottom of the flanges *g*, so that the girders *D*, shall be on the outside of the wooden casing formed around the bottom *B*. 70 75

What I claim as my invention is— 80

1. In a bath-tub, a metal frame for the end thereof, having a flange to receive and support the inner lining, a second flange to support a casing, said casing forming a chamber under the inner lining, and a burner placed 85 in said chamber and adapted to heat the contents of the tub, substantially as described.

2. A metal frame for the end of a bath-tub and consisting of corner posts shaped to receive and hold the wooden side casing, a cross-flange to support the bottom of the wooden casing and a curved cross-flange to support the inner casing, substantially as and for the purpose specified. 90

3. A metal frame for the end of a bath-tub 95 and consisting of corner posts *d*, shaped to receive and hold the wooden side casing, a cross-flange *e*, to support the bottom of the wooden casing, a curved cross-flange *a*, to support the inner casing, and a flange *h*, to sup- 100

port a cap-piece, substantially as and for the purpose specified.

4. A bath-tub composed of a metal frame at each end having flanges *a* and *h*, a metal lining *B*, resting at each end on the said flanges *a*, in combination with a wooden casing held by the

flanges *h*, substantially as and for the purposes specified.

Toronto, March 17, 1893.

FREDERICK J. H. HAZARD.

In presence of—

J. EDW. MAYBEE,

W. G. McMILLAN.
